FRANK DOVERSPIKE, OF CHICAGO, ILLINOIS.

TYPEWRITER ATTACHMENT.

Application filed August 19, 1925. Serial No. 51,170.

This invention relates to new and useful improvements in typewriter attachments, and more particularly to such a device adapted for use to take the place of the usual carbon paper employed in conjunction with a typewriter for making duplicates or carbon copies.

An object of the invention is to provide a typewriter attachment having means for readily and conveniently connecting it to the usual platen carriage of a standard typewriter without the necessity of making any changes or alterations in the design of the typewriter and which will not affect the usual operation of the typewriter.

A further object of the invention is to provide such an attachment employing one or more ribbons adapted to be brought into position in front of the platen and back of the usual main record ribbon provided on the typewriter, whereby one or more ink copies may be made without the use of the carbon paper sheets usually employed for this purpose.

25 A further object is to provide a typewriter attachment for making carbon copies comprising a supplemental frame adapted to be detachably connected to the usual platen carriage of the typewriter, and which frame is provided with a ribbon supporting means so constructed that the relative position or positions of the ribbon or ribbons may be laterally shifted with reference to the typewriter platen when it is found desirable to present fresh printing surfaces of the ribbons to the point of impact of the type.

30 A further object is to provide such an attachment having means for maintaining the effective length of the supplemental ribbons under tension, thereby insuring a clean-cut imprint being made upon the sheet of paper being printed each time a type is actuated.

35 A further object is to provide such an attachment which is simple and inexpensive in construction and which will be positive and foolproof in operation.

The particular object of the invention therefore is to provide an improved typewriter attachment particularly adapted for 40 use in conjunction with ordinary typewriters for making duplicates or ink copies without the use of the usual carbon paper.

45 Other objects of the invention will more fully appear from the following description

and the accompanying drawings and will be 55 pointed out in the annexed claims.

In the drawings there has been disclosed a structure designed to carry out the various objects of the invention but it is to be understood that the invention is not confined to the exact features shown, as various changes may be made within the scope of the claims which follow.

In the accompanying drawings forming 65 part of this specification,

Figure 1 is a view in side elevation of an ordinary typewriter showing the improved attachment mounted thereon;

Figure 2 is a front view of Figure 1 showing the inking ribbons in raised inoperative 70 position;

Figure 3 is a plan view of Figure 2;

Figure 4 is an enlarged detail sectional view on the line 4—4 of Figure 2 showing the inking ribbons raised and also how the 75 sheets of paper to be typed are inserted therebetween;

Figure 5 is a similar view showing the paper sheets positioned upon the typewriter platen and the inking ribbons in lowered operative position;

Figure 6 is an enlarged detailed view in perspective showing the means provided for supporting the inking ribbons and also showing how they are separated when in inoperative position;

Figure 7 is a similar view showing the relative position of the ribbons when in operative position;

Figure 8 is an enlarged detail sectional 90 view showing how a plurality of sheets may be typed at one time;

Figure 9 is a detail sectional view on the line 9—9 of Figure 3 showing one of the pins upon which the spools supporting the 95 copying ribbons are mounted;

Figure 10 is a front view on the line 10—10 of Figure 11 showing a modified construction employing one inking ribbon only;

Figure 11 is a plan view of Figure 10, and 100

Figures 12 and 13 are detail views showing how the inking ribbon is supported on the supporting members provided therefor, and also showing the preferred method of detachably mounting a guard ribbon thereon to prevent the inking ribbon from contacting with the back side of the original 105 typed sheet.

The novel typewriter attachment featured in this invention includes a supplemental frame adapted to be detachably secured to the usual platen carriage of the typewriter so as to travel as a unit therewith when the typewriter is in operation. The supplemental frame of the attachment preferably comprises an intermediate section 13 having side portions 14 provided thereon which are apertured to receive suitable pivot studs or screws 15 pivotally mounted in apertures provided in the side members 16, as shown in Figures 1, 2 and 3. A thumb screw 17 is mounted on each stud 15 to lock the side portions 14 of the intermediate frame section 13 in adjusted positions as indicated in full and dotted lines in Figure 1.

The means provided for supporting the inking ribbons preferably consists of a pair of ribbon-supporting members or bars 18 and 19 mounted in guides 21 and 22 provided at the juncture between the intermediate frame section 13 and the side portions 14, as particularly shown in Figures 6 and 7. Each ribbon-supporting bar has secured to its lower end a ribbon guide 23 adapted to receive the inking ribbons 24 and 25 as shown. Links 26 are pivotally connected to the upper ends of the forward supporting members 19 by means of shouleder studs 27, preferably secured to the supporting members. Each stud 27 extends through its complementary link 26 and through an elongated aperture or slot 28 provided in the adjacent supporting member 18 (see Figures 6 and 7). The opposite ends of the links 26 are pivotally connected to a pair of bell cranks 29 and 31 which are operatively connected together by means of a connecting link 32, as shown in Figure 3. An operating lever 33 is preferably provided on the bell crank 31 whereby the two bell cranks may be simultaneously operated to actuate the ribbon-supporting members 18 and 19. The purpose of the slots 28 in the supporting members 18 is to provide means for separating the inking ribbons 24 and 25, when in raised inoperative position as shown in Figures 2, 4 and 6. By thus separating the ribbons, the operation of inserting the sheets of paper therebetween will be greatly simplified as is clearly shown in Figure 4. If the two ribbons were not separated or spaced one above the other as above described, it would be necessary to insert a pencil or other device between the two ribbons to separate them sufficiently to permit the insertion of a sheet of paper therebetween.

Figures 4 and 5 illustrate the proper location of the platen roller 34 with relation to the attachment when the latter is mounted upon the typewriter. Figure 4 illustrates one use of the attachment wherein three sheets of paper are shown partially inserted

therein to be typed, the inside sheet being placed directly against the platen roller and the second sheet between the two copying ribbons, and the third or original between the first copying ribbon and the usual record ribbon 35 of the typewriter. Figure 5 illustrates the proper position of the sheets upon the platen roller when ready to be typed. In this figure, it will be noted that the copying ribbons 24 and 25, when downwardly moved into operative position, will be substantially aligned with the usual ribbon 35 of the typewriter and also in horizontal alignment with the selected type of the type bar 36 so that when the latter is actuated to make an impression, such impression will be imprinted upon the three sheets of paper.

A feature of this invention resides in the novel means provided for automatically increasing the tension in the copying ribbons when moved from the full line position shown in Figures 2 and 4, to the dotted line position in Figure 2 and full line position shown in Figure 5. When the ribbons are in the full line position shown in Figure 2, they are out of alignment with the type bar 36 and therefore need not be under as much tension as is desirable when they are downwardly moved into operative position in line with the type bar. Referring to Figure 2, it will be noted that the guides 21 and 22 for the ribbon supporting members 18 and 19 are not parallel, but slightly diverge toward their lower ends so that when the copying ribbons are moved downwardly from the full line to the dotted line position in Figure 2, the lower ends of each pair of the supporting members will tend to spread or move away from each other, thereby automatically increasing the tension in the ribbon. Conversely, when the ribbons are upwardly moved to the full line position in Figure 2, the lower ends of each pair of supporting members will be inwardly moved toward each other, thereby decreasing the tension in the ribbons. The ends of each copying ribbon are mounted upon a pair of spools 37 as shown in Figures 1 and 3. The spools 37 are similar in construction to the spools 38 which support the usual ribbon 35 of the typewriter, shown in dotted lines in Figure 3. Each spool 37 is demountably and rotatably mounted upon a pin 39 secured to the horizontal web 41 of the side frame members 16 as shown in Figure 9, to which the intermediate frame section 13 is pivotally mounted. The upper end of each pin 39 is preferably grooved, as shown, to receive a clip 42 which functions to retain the spools upon the pins 39 and also to detachably secure the operating cranks 43 to the pins 39. The cranks 43 are also provided with means, not shown, for securing them to the spools whereby when they are rotated, a similar movement will be

imparted to the spools 37 to laterally shift the position of the ribbon with respect to the center line of the typewriter or the type bar for the purpose of presenting a fresh inking surface for the type bar.

A tension means is also provided for each spool 37 to maintain the ribbons under a constant tension whether in operative or inoperative position, thereby preventing the 10 ribbons from sagging, which might interfere with their operation. Referring to Figure 3, it will be noted that a tension member 44 is pivotally mounted upon each pin 39 between a flange 45 provided thereon and 15 the horizontal web 41 of the side frame members, see Figure 9. A ribbon guide 46 is secured to one end of each extension member adapted to receive its complementary ribbon as shown on the left hand side of 20 Figure 3. The opposite end of each tension member 44 has one end of a tension spring 47 secured thereto which has its opposite end connected to the web 41 of the side frame member 16 as shown in Figure 3. When 25 the ribbon spools are mounted upon the pins 39 as shown at the right hand side of Figure 3, and the ribbons are passed through the guides 46, the inner ends of the tension members 44 will tend to oscillate upon the pins 39 as a center, thereby causing the outer ends thereof to outwardly move with the result that the springs 47 will be put under tension, thereby causing the ribbons to be likewise put under tension. A small friction 35 lever 48 is pivotally mounted on each tension member 44 adjacent the springs 47. These friction levers are adapted to be oscillated upon their pivots 49 so as to cause the tabs or projections 51 thereof to be inwardly 40 moved over the lower flange of each spool 37, thereby frictionally holding the lower flange of each spool 37 against the enlarged circular portions 52 of each side frame member 16. It is to be understood that the projections 51 of the friction levers 48 are so shaped and formed that when they are moved over the lower flanges of the spools 37 they will exert a downward pressure thereagainst to frictionally prevent the 45 spools from rotating. When the levers are outwardly swung to the position shown on the right hand side of Figure 3, the spools 37 will be free to rotate so that the position of the ribbons may be readily and conveniently shifted with respect to the type bar after which the friction levers 48 are inwardly moved into engagement with the spools 37 as shown on the left hand side of 50 Figure 3 wherein it will be noted that the spools will be prevented from rotating upon the pivot pins 39 and the springs 47 will, therefore, be put under tension thereby imparting a similar tension to the ribbons. 55 Each tension member 44 is preferably provided with a stop lug 53 adapted to engage

the inner edge of the frame 41 to limit the movement thereof.

Another feature of this invention resides in the means provided for holding the sheets of paper being typed against the periphery 70 of the platen roller. Such means preferably consists of a roller 54 mounted upon a rod or shaft 55 having its ends pivotally mounted in bearings 56 provided upon a U-shaped bar 57 having its ends pivotally connected 75 to the end frame members 16 by means of pivots 58. Tension springs 59 are provided at each end of the U-shaped bar 57, each having one end connected to the bar and their opposite ends to the side frame members 16 as shown in Figures 4 and 5. These springs are so arranged as to yieldably retain the roller 54 in either of its positions as shown. When the roller 54 is swung from its inoperative position in engagement with the piece of paper, as shown in Figure 5, the lower ends of the tension springs 59 will pass over the centers of the pivot pins 58 thereby causing the roller to be yieldably held against the paper and likewise to be yieldably held in raised inoperative position 80 against a pair of stop lugs 61 formed upon the brackets 62 to which the ends of the U-shaped bar 57 are pivotally connected. These brackets are suitably secured to the side frame members 16. By the provision of the roller 54, the usual means provided on a typewriter for holding the paper against the platen roller may be dispensed with as the sheets of paper, especially when a plurality of sheets are being typed, may be more firmly held against the platen roller by means of the roller 54 as shown in this invention. 85

Figure 8 is an enlarged detail sectional view illustrating how a plurality of sheets of paper may be typed at one operation. 90

In the illustration, here shown, five sheets are printed, one original and four carbon copies. When the four copies are thus typed, by the use of only two copying ribbons in connection with the original ribbon 35 of the typewriter, the original sheet A and the first copy B are placed between the original typewriter ribbon 35 and the front copying ribbon 24 as shown. The second and third copies C and D are placed between the two copying ribbons while the fourth copy E is placed between the ribbon 25 and the platen roller 34. When five sheets are thus typed at one operation, the first and third copies B and C are preferably of a very thin paper which is sufficiently transparent to permit the impression of the letter or character, made by the impact of the type bar 36 with the ribbon 35, to be visible therethrough as it will readily be noted by closely observing the figure that the copies B and D will be printed upon their backs or opposite 100 sides with reference to the original and sec-

ond and fourth copies, which will be printed upon the front exposed sides of the material. When two copies are made as shown in Figures 1, 4 and 5, they will be arranged as shown and as hereinbefore described. When but one copy is desired, the two copying ribbons are preferably placed between the two sheets.

From the foregoing, therefore, it will readily be seen that by the use of the two supplementary inking ribbons 24 and 25, that a plurality of ink copies may be made in one operation without the use of the usual carbon paper for making such copies. Also by causing the ribbons 24 and 25 to automatically become separated from one another as shown in Figures 4 and 6, when in raised inoperative position, the operation of inserting the paper sheets therebetween is greatly simplified. Also as a result of the intermediate frame section 13, carrying the ribbon-supporting members 18 and 19, being pivotally mounted as particularly shown in Figures 1, 4 and 5, the frame section 13, and therefore the forward portions of the ribbons, may be upwardly swung to the position shown in dotted lines in Figure 1 so that if desired, the typewriter may be used in the ordinary manner employing carbon paper for making carbon copies.

The side frame members 16 are detachably connected to the platen carriage by means of tension clips 63 secured to the horizontal webs 41 of the frame members, and having their lower end-portions adapted to engage the ends of the platen carriage as shown in Figures 1 and 2, the end 64 of the carriage being shown in dotted lines in Figure 2.

Figures 10, 11, 12 and 13 illustrate an attachment of modified construction employing one inking ribbon only. In the construction here shown, the ribbon 65 is similarly supported in guides 66, secured to the lower ends of the upright supporting members 67 as shown in Figures 12 and 13. The ends of the ribbon are similarly mounted upon the spools 37 which are rotatably and detachably mounted upon the pivot pins 39 as shown and described with reference to the previous figures. The ribbon supporting members 67 are similarly operated by means of a pair of bell cranks 29^a and 31^a, the latter having an operating handle 33^a provided thereon for the convenience of the operator in actuating the bell cranks to pivot the ribbon from the full line to the dotted line position shown in Figure 10 and vice versa.

In the construction here shown, a guard ribbon 68 is also preferably provided in front of the inking ribbon 65 to prevent the original sheet of paper from contact with the inking ribbon 65 when being typed. The ends of this guard ribbon are detachably secured to the lower ends of the upright supporting members 67 by means of pivoted

clamps 69, each having its lower end formed with a hook 71 adapted to engage the lower edge of a depending plate 72 over which the ends of the guard ribbon 68 are folded, as particularly shown in Figure 12. A plurality of teeth or points 73 are preferably provided on the edge of each plate 72 to engage the guard ribbon, thereby preventing it from slipping or becoming loosened when the clamp 69 is in the position shown, with the ends of the guard ribbon clamped against the plate 72. The guard ribbon 68 may readily be removed by outwardly swinging the clamps 69 to the dotted line position shown in Figure 12, after which the ribbon ends may readily be disconnected from the teeth 73 and a new one mounted thereon.

I claim as my invention:

1. A typewriter attachment for making copies, including a supplemental frame having means for connection with the platen carriage of a typewriter, means for supporting a pair of ribbons and guiding the same in parallel relation with and in front of a typewriter platen, comprising two pairs of slidably supported members having ribbon guides, the members of each pair having a link-and-slot inter-connection, to obtain a non-horizontally aligned disposition of one member of each pair, at one limit of translation, and manually operable means connecting with the inter-connection links for simultaneously translating both pairs either upwardly or downwardly.

2. A typewriter attachment for making carbon copies, including a supplemental frame having means for connection with the platen carriage of a typewriter, an inking ribbon, means for supporting and guiding said ribbon in front of the typewriter platen comprising members slidably mounted in said frame, a bell crank connected to each member, and an operating lever connected to said bell cranks whereby said members may be simultaneously actuated to move the ribbon into and out of operative position in front of the typewriter platen.

3. A typewriter attachment for making copies, including a supplemental frame having means for connection with the platen carriage of a typewriter, means for supporting a pair of ribbons and guiding the same in parallel relation with and in front of a typewriter platen, comprising two pairs of slidably supported members having ribbon guides, the members of each pair having a link-and-slot inter-connection, to obtain a non-horizontally aligned disposition of one member of each pair, at the upper limit of translation, and for obtaining horizontal alinement at printing position, and manually operable means connecting with the inter-connection links for simultaneously operating both pairs upwardly and downwardly.

4. A typewriter attachment for making copies, including a supplemental frame having means for connection with the platen carriage of a typewriter, an inking ribbon, 5 supports slidably borne by said frame and whereon said ribbon is mounted, and guides for said supports having their lower ends diverging, thereby causing the lower ends of said supports to spread when downwardly moved, and automatically increasing the tension of said ribbon when moved into operative position in front of the typewriter platen. 10
5. A typewriter attachment for making copies, including a supplemental frame adapted to be demountably connected to the platen carriage of a typewriter, two pairs of translatable mounted ribbon guide supporting members, a link between the members of 15 each pair having a pivotal connection with one member and a limited translative and pivotal connection with the other member, and manually operable means for simultaneously raising or lowering the links. 20
6. A typewriter attachment for making copies including a supplemental frame adapted to be demountably connected to the platen carriage of a typewriter, an inking ribbon, spools for supporting said ribbon rotatably mounted upon said frame whereby 25 said ribbon may be adjusted longitudinally to present a fresh printing surface to the type, and means adapted to maintain said ribbon under constant tension, said means comprising lever-like guide and tension members, one pivoted co-axially with the axis of each spool and having its ribbon guide disposed beyond the spool periphery. 30
7. A typewriter attachment for making 40 copies, including a frame adapted to be mounted upon the platen carriage of a typewriter, plural pairs of ribbon supporting members translatable mounted in said frame, a link interconnecting the members 45 of each pair, said link pivotally connected with one member and having a limited sliding connection with the other, and manually operable means connecting with the links for raising and lowering the same. 50
8. A typewriter attachment for making copies including a frame adapted to be mounted upon the platen carriage of a type- writer, a plurality of spools mounted on said frame, a pair of inking ribbons adapted to have their end portion connected to said spools, ribbon supporting members mounted in guides in said frame, an operating lever for actuating said supporting members to move the ribbons into and out of working and non-working positions, and means for separating said ribbons when in non-working position to permit convenient insertion of paper therebetween, said means comprising elongated apertures in two of said supporting members whereby, when all of 60 said members are moved into non-working position, said ribbons will be out of horizontal alinement. 65
9. A device of the class described including a frame having plural pairs of ribbon carriers and guides slidable therein, link and slot connections between the members of each pair for moving one member by the other to obtain translation of one in advance of the other, to bring the ribbons carried by respective pairs into opposition at one limit position of the carriers, and to non-oppositely dispose the same at an opposite limit position, and an operating lever having connections with the links for simultaneously 70 moving said links in opposite directions. 75
10. A device of the class described comprising a first frame attachable to a typewriter carriage and having ribbon spools thereon, a second frame pivoted to the first 80 and having a pair of ribbon carriers slidable therein, each carrier having a guide providing angularly related arms respectively extending in direction of the ribbon spools and toward the guides of opposite carriers, the 85 first-mentioned guides being open at the top and the last mentioned closed thereat whereby when the carriers are translated to bring the guides to points on one side of the plane of the spools, or when the second frame is 90 rotated to dispose the guides at the opposite side of that plane, the ribbon is free to rise in the first-mentioned guides, whereby the two arms of each guide co-act to prevent escape of the ribbon. 95

In witness whereof, I have hereunto set my hand this 15th day of August, 1925.

FRANK DOVERSPIKE.
